LASTING STAND

Filed Aug. 4, 1921

2 Sheets-Sheet 2

UNITED STATES PATENT OFFICE.

JOHN ANDREW, OF CONCORD, NEW HAMPSHIRE.

LASTING STAND.

Application filed August 4, 1921. Serial No. 489,737.

To all whom it may concern:

Be it known that JOHN ANDREW, citizen of the United States, residing at Concord, in the county of Merrimack and State of New Hampshire, has invented certain new and useful Improvements in Lasting Stands, of which the following is a specification, reference being had therein to the accompanying drawing.

10 My invention relates to new and useful improvements in a shoemaker's lasting stand and has for its principal object the construction of the stand in such a manner that lasts of various sizes may be used, said lasts being detachably connected to the stand.

15 Another object resides in the construction of the stand in such a manner that it may be rotated to different positions so that the user may easily work upon the boot or shoe carried upon the last.

20 As a further object I provide adjustable means for holding the boot or shoe upon the last while working thereon.

25 With the above and other objects in view, which will appear as the description proceeds, my invention consists in the novel detail of construction and arrangement of parts described in the following specification and illustrated in the accompanying drawings, 30 and while I have illustrated and described the preferred embodiments of my invention it will be understood that such changes may be made as will fall within the scope of the appended claim.

35 In the drawings:—

Fig. 1 is a side elevation.

Fig. 2 is a section on the line 2—2 of Fig. 1, looking in the direction of the arrows.

Fig. 3 is a top plan.

40 Fig. 4 is a horizontal section on the line 4—4 of Fig. 1 looking in the direction of the arrows.

Fig. 5 is a front elevation with parts shown in vertical section.

45 Fig. 6 is a top plan of the operating lever, and

Fig. 7 is a side elevation of a slightly modified form of the invention.

50 In the drawings 1 indicates a base having the upwardly extending arm 2 which is formed at the top with the vertically extending sleeve 3 in alignment with a recess 4 formed in the upper surface of the base for a purpose to be later described. Upwardly extending ears 5 are also formed on the base 1, adjacent the recess 4, and pivotally con-

nected to the ears or lugs 5 is a foot treddle 6 the inner end of which is reduced as shown at 7.

55 A standard 8 has a reduced lower portion 9 which extends through the sleeve 3 with its lowermost end received in the recess 4 of the base. The standard is rotatable and has the collar 10 secured adjacent the lower end by means of the transversely extending pin 11. The collar 10 is provided with a plurality of circumferentially spaced notches 12 in which the reduced extension 7 of the foot treddle 6 is adapted to be received to hold the standard in adjusted position against 60 rotation. A spring 13 will be interposed between the base and the outer end of the treddle 6 so as to normally hold the end 7 of the treddle within one of the notches.

65 Secured to the standard 8 is a casting 14 having the vertically extending opening 15 therein, said opening 15 receiving the shank 16 of the rotatable pin 17 having the transversely extending eye 18. A segmental casting 19 is secured to the standard 8, on the opposite side to the casting 14 and is provided on its curved face with the ratchet teeth 20. A lever 21 is pivotally connected to the pin 17 by means of the transversely extending pin 22 which passes through the eye 18 in the pin, the end of said lever being forked to provide the arms 23 which straddle the standard 8 as well as the pin 17, the arms being provided with openings to receive the transversely extending pivot pin 90

70 22. One of the arms 23 is provided with the inwardly extending inclined lip 24 which is adapted to engage the ratchet teeth 20 of the segmental casting 19 to hold the lever in different vertical adjusted positions for a purpose which will later appear. The upper end of the standard 8 is provided in opposite faces with recesses 25 to receive the inwardly extending spaced lugs or arms 26 of the last 75 27. The lugs 26 will straddle the upper end of the standard so that a lug will be received in each of the recesses 25 on the opposite faces of the standard.

80 For securing a boot or shoe upon the last 27 I provide an adjustable strap 28 said strap provided on each end with a loop 29 to which is connected one end of a coiled spring 30, the opposite end of the spring being secured to one of the arms 23 of the lever 21 by means of a screw or bolt 31 which is threaded into 105 an opening 32 formed in the arm.

85 In Fig. 7, I have shown a slightly modified

form of the invention in the form of a smaller stand more particularly adapted to use while the user is sitting. In this form of the invention I provide a base 33 having the upwardly extending standard 34 preferably formed integral therewith, the upper end of the standard provided on opposite faces with recesses 35 adapted to receive the downwardly extending spaced lugs or arms 26 of the lasts 27.

From the above it will be seen that I have provided a lasting stand in which the lasts are detachable and interchangeable so that lasts of various sizes may be used. The downwardly extending lugs or arms 26 formed on the lasts being received in the recesses formed in the upper end of the standard provide easy means for connecting the lasts to the standard and at the same time securely hold them against accidental displacement. In the preferred form of the invention illustrated in Figs. 1 to 6 inclusive the standard is rotatable so that the last may be swung to different positions to be within convenient reach of the user. When the standard is locked against rotation the reduced end 7 of the foot treddle 6 will be received in one of the notches 12 of the collar 10, the spring 13 holding the outer end of the treddle up. When it is desired to rotate the standard the outer end of the foot treddle is engaged and depressed so as to raise the reduced end 7 thereof out of the notch 12. When this has been done the standard may be rotated into desired position and the end 7 will then be received in one of the other notches 12, the notches, as previously stated, being circumferentially spaced. When the boot or shoe is placed upon the last 27 it is often desirable that some means be provided for holding the same thereon and for this purpose I have the strap 28 which is yieldably connected to the lever 21 by the coil springs 30. The lever may be swung into lowered position to tighten the strap and securely hold the boot or shoe or may be raised to disengage the strap. The pin 17, being rotatably connected to the casting 14, allows the lever 21 to be

swung horizontally to engage or disengage the lip 24, of the lever with the ratchet teeth 20 of the segmental casting 19. The coil springs 30 allow the strap 28 to be adjusted, if desired, with respect to the last 27, without operating the lever 21.

As previously stated the modified form of the invention shown in Fig. 7, is of much smaller size than the preferred form and is more particularly adapted for use while the user is in sitting position. In this modified form the standard is not rotatable but is preferably formed integral with the base 33, although it will be understood that if desired, the standard might be fastened to the base in any desired manner.

Having fully described my invention what I claim as new and desire to secure by Letters Patent is:

A lasting stand comprising a standard, a last carried by the standard, a casting secured to one side of the standard and having a vertically extending opening therein, a pin rotatably carried in the vertically extending opening and extending parallel with the standard, said pin having an enlargement on the upper end bearing upon the top of the casting and provided with a transversely extending opening, teeth on the opposite side of the standard, a forked lever straddling the teeth and the standard, a pin extending through the forked end of the lever and the transversely extending opening of the first mentioned pin for pivotally connecting the lever to the enlargement of the pin, a lip formed on one arm of the forked lever for engagement with or disengagement from the teeth upon horizontal swinging movement of the lever, and a strap connected to the lever and normally extending over the last, said strap being moved relative to the last upon vertical movement of the lever.

In testimony whereof I hereunto affix my signature in the presence of two witnesses.

JOHN ANDREW.

Witnesses:

NELSON A. BRYANT,
JOHN P. CHAMBERS.
